UNITED STATES PATENT OFFICE.

ABRAHAM DE WITT, OF BLUFFTON, INDIANA.

MEASURING-VESSEL.

SPECIFICATION forming part of Letters Patent No. 409,023, dated August 13, 1889.

Application filed April 9, 1889. Serial No. 306,541. (No model.)

To all whom it may concern:

Be it known that I, ABRAHAM DE WITT, a citizen of the United States of America, residing at Bluffton, in the county of Wells and 5 State of Indiana, have invented new and useful Improvements in Measuring-Vessels, of which the following is a specification.

My invention has relation to improvements in metallic measuring-vessels of that class or 10 style used for holding a quantity of liquid and adapted to discharge a desired measure of its contents, and the object is to simplify and improve existing devices of the kind.

I have clearly and fully illustrated my in- 15 vention in the accompanying drawings, forming a part hereof, wherein—

Figure 1 is a view of the complete vessel. Fig. 2 is a central vertical section of the same with the delivery-spout turned to discharge 20 the contents. Fig. 3 is a view of the valved plunger or piston. Fig. 4 is a plan view of the lid or cover of the vessel.

A designates the body of the vessel, formed into a true cylinder 1 and provided with a 25 flat bottom 2, and a handle or bail 3 attached to the shell of the vessel, as usual. On the side of the shell is secured a vertically-ar- ranged tube 4, which consists of a semicircu- lar shell having its edges sealed by solder to 30 the face of the vessel, so that the shell of the vessel at that part constitutes a part of the interior of the tube. This construction se- cures the tube firmly to the can and prevents it from being disturbed or displaced by ex- 35 terior influences. The ends of the tube at the top and bottom are closed exteriorly; but openings 5 6 are formed in the shell at the re- spective ends, the former of which serves as an exit-port from the vessel to the tube

40 through which the fluid is forced, and to the latter opening 6 is rigidly connected a pipe 7, the upper end of which projects a short dis- tance above the rim of the vessel, as shown, in order that the end may enter and connect 45 with the swiveled nozzle or discharge-pipe. The fluid on the pressure of the piston or plun- ger is forced through the opening 5, thence up through the tube on the outside of the shell, through the interior pipe 7, and through 50 the swiveled nozzle into the receiving-utensil.

B designates the lid or cover, which fits

snugly in place on the vessel and is provided with a filling-port 8, having a threaded cap 9 fitted thereto. The nozzle 10 consists of an arched or curved pipe, having its one end 11 55 attached to the cover, so as to turn outward, as seen in Fig. 2 of the drawings, and when not in use that it may be swung or turned back, with its free end in the drip-well or seat 12, as seen in Fig. 1 of the drawings. This drip-well con- 60 sists of a screw-cap fitted in the cover and formed with a hole 13, over which the free end of the nozzle rests when it is turned to that position, as shown. The hole 13 not only serves to permit the drip to find its way back 65 into the vessel, but also serves as an air-hole to facilitate the filling of the vessel through the filling-hole. In the center of the cover is a piston-rod aperture 14, through which rod 15 of the piston is passed and slides. On the 70 lower end of the piston-rod is secured the pis- ton 16, which has its rim provided with suit- able packing 17 to make it fit fluid-tight in the shell of the vessel. The piston is formed with ports 18, and on the under sides are secured 75 valves 19 20, arranged to open and permit the piston to be drawn up and leave the fluid es- cape below the piston, and to close and seal the ports of the piston when a downward movement takes place. On the piston-rod are 80 marked graduations 21, which indicate the height to which the piston must be lifted from the bottom of the vessel to discharge a cer- 85 tain quantity of fluid when pushed down again to the bottom.

The functions of the several parts have been stated in connection with their description; but the operation may be rehearsed as fol- 90 lows: When it is desired to discharge liquid from the vessel, the nozzle is turned from its position on the cover to an outward position. The piston is then lifted until the measure desired is indicated by the graduation, when the piston is forced down, and the result is the 95 discharge of the required quantity of the con- tents.

Having thus described my improvements, so as to distinguish them from other inven- tions, I proceed to particularly point out and distinctly claim the parts, improvements, and 100 combinations.

I claim as my invention as follows:

1. The combination, with the cylindrical vessel A, provided with the ports at its top and bottom, the tube 4, opening into the said ports, and the interior pipe 7 on the upper port, of the cover B, provided with a drip-hole and nozzle-seat, the swiveled nozzle in the cover, and the valved piston, substantially as described.

2. The combination of the cylindrical vessel A, provided with the pipe 7 at its upper end, and the semicircular shell or tube secured on the outer face of the vessel and opening into the vessel at its bottom and into the pipe at its top, the cover provided with a drip-hole and nozzle-seat, the swiveled nozzle on the cover, and a valved piston provided with a piston-rod having graduations of measures marked thereon, substantially as described, and for the purpose specified.

3. The combination, with the vessel A, provided with a vertically-arranged exterior discharge-tube opening into the vessel at the top and bottom, and an interior vertical pipe opening into the said tube, a reciprocating piston and cover, of the swiveled nozzle arranged to connect with the interior pipe of the vessel at its swiveled end and to turn and set in a drip-hole in the cover with its free end, substantially as described.

In witness whereof I hereunto set my hand 30 in the presence of two attesting witnesses.

ABRAHAM DE WITT.

Attest:

LEVI MOCK,
JOSEPH S. DAILEY.
